UNITED STATES PATENT OFFICE.

FRANCIS HATMAKER, OF PITTSTON, PENNSYLVANIA.

TELEGRAPH-SOUNDER.

SPECIFICATION forming part of Letters Patent No. 650,836, dated June 5, 1900.

Application filed July 31, 1899. Serial No. 725,609. (No model.)

To all whom it may concern:

Be it known that I, FRANCIS HATMAKER, a citizen of the United States, residing at Pittston, in the county of Luzerne and State of Pennsylvania, have invented certain new and useful Improvements in Telegraph-Sounders; and I do hereby declare the following to be a full, clear, and exact description of the invention, such as will enable others skilled in the art to which it appertains to make and use the same.

This invention relates to improvements in telegraph-sounders, and one of the objects is to produce a clearer and more audible sound. Another object is to produce a device of this class with few parts and otherwise simple in construction and generally to promote the durability of the instrument.

A further object is to provide the instrument with an improved tension device for the armature-lever which will permit a quick and accurate adjustment thereof.

With these and other objects and advantages in view the invention consists of certain novel and useful combinations and arrangements of parts, described in the following specification, and particularly pointed out in the claims appended thereto.

In the drawings accompanying this specification and illustrating my invention, Figure 1 is a side elevation of the improved telegraph-sounder. Fig. 2 is a rear elevation thereof. Fig. 3 is a detail view. Fig. 4 is a sectional view of a modified form of base; Fig. 5, detail views of modified form of base-legs.

Like letters of reference denote like parts throughout the several figures of the drawings.

A is the base of the sounder, which is preferably constructed of metal to prevent cracking when secured to a table or other support. It is provided with a rear leg and two forward ones. A screw-hole is also provided whereby the said base may be fastened in position. At each rear corner is a binding-post A', provided with the usual clamp member a, and said binding-post is secured to the base by the threaded bolt a', which passes through the post, with an upper projection for the clamp member a, and a lower projection which passes through a perforation or open-

ing a² in the base. It is insulated therefrom by upper and lower washers a³ and a⁴, of rubber or any other suitable insulating material; and the gasket a⁵, of similar insulating material, which may be formed integral with the upper washer a³. This gasket surrounds the bolt where it passes through the base. The washer a⁶ and nut a⁷ fasten the binding-post in place.

Secured upon the base A, with a space therebetween, is a sounding-plate B, which is rendered free to vibrate by having one point of contact with the base at its front, the washer b, and two points of contact at the rear, one at each corner b'b'. These washers, or more properly "spacing-sleeves," surround the screws which secure the sounding-plate to the base. Upon this plate B is mounted the usual sounding-post C, which is provided with the usual adjusting-screw c to lengthen or shorten the stroke of the armature-lever D. This lever has secured to it in the well-known manner the armature d of the magnets E E, which may be the ordinary coil-magnets, and these magnets are electrically connected to the binding-posts in the manner well known to those versed in the art. These connections are insulated from the base by the rubber sleeves e e.

The armature-lever D is provided with trunnions d' d' or may be a shaft a short distance from the rear thereof, which are pivotally mounted in a yoke F by the countersunk screws f f, passing through opposite sides of the yoke horizontally and engaging with sockets in the ends of the trunnions. This yoke is supported upon a standard F', with which it may be formed integral, and the foot of said standard is reduced and squared, as at f', and stepped in a square opening in the sounding-plate B. This prevents the yoke from being turned in its place, as would be the case were the opening and foot round, with constant vibrations of the armature-lever acting thereupon. Below the sounding-plate the foot is further reduced and screw-threaded to receive a fastening-nut f², which secures the yoke firmly in position.

The tension device which normally keeps the armature and armature-lever raised consists of a bowed spring G, which may be constructed of flat or round spring metal. One

arm or branch of this spring may be secured to the under side of the rear end of the armature-lever D by any fastening means—such, for example, as a screw—or it may be secured 5 to any side of the said lever or it may be inserted in the end thereof, which may be split or slotted for that purpose. The other branch of the bowed spring is bent upwardly at right angles, as at g, and a perforation g' made 10 therein to pass over a threaded adjusting-bolt g², which passes horizontally through the top of the yoke. The perforation g' is larger than the diameter of the bolt, and on the end of the latter, retaining the end of the spring 15 in place, is a square nut g³, which is large enough to abut against the bow of the spring and not turn with the bolt. By this means the bolt can be manipulated to increase or diminish the tension of the lower arm of the 20 spring by shortening or lengthening the said arm, and thereby to accurately regulate the resistance to the contrary force exercised by the magnets upon the armature when the circuit is made. By securing one branch of this 25 bowed spring fast to the top of the yoke and securing the other branch to the under side of the end of the armature-lever in the above-described adjustable manner the same nicety of regulation of the resistance will be obtained.

I may employ a modified form of base, as seen in Fig. 4. Here the base II may be formed of thin sheet metal, as brass, and separate legs of tubing-sections, as h, employed 35 to raise said base from the supporting-table X. Screws h' are passed down through the base and tube legs h and into the table, or I may employ separate legs, made of wire, in the shapes illustrated in Fig. 5, h², which 40 serve to raise the base above the table, and screws h' are passed down therethrough the same as with the legs made of tube-sections.

This completes the construction, and therefrom the operation will be apparent without explanation of the same.

45

I do not desire to limit myself to the precise details of construction or arrangement of parts, but reserve to myself the right and privilege to alter the same within the bounds of mechanical skill without departing from 50 the spirit of my invention.

Having thus fully described my invention, what I claim as new, and desire to secure by Letters Patent, is—

1. The combination with a base and suitable electrical connections, a sounding-post, magnets, an armature and armature-lever pivotally supported in position, of an adjustable tension device for said lever, consisting of a bowed spring connected to the lever and 60 to the lever-support, and means for varying the length of the arm of the spring, connected to the lever, to regulate the tension on the end of the same.

2. The combination with a base, and suitable electrical connections, a sounding-post, magnets, an armature and armature-lever pivotally supported in position, of a tension device for said lever, consisting of a bowed spring connected to the lever and means for 70 varying the length of the arm of the spring connected to the lever, comprising a threaded adjusting-bolt passing through an opening in the yoke and an opening in the free arm of the spring, and a retaining-nut on the end of 75 said bolt, held against rotation by contact with the arm of said spring.

In testimony whereof I affix my signature in presence of two witnesses.

FRANCIS HATMAKER.
